UNITED STATES PATENT OFFICE.

NICHOLAS MONSHAUSEN, OF MILWAUKEE, WISCONSIN, ASSIGNOR TO
ENAMELED STEEL ROOFING COMPANY, A CORPORATION OF WIS-
CONSIN.

ROOFING-TILE.

SPECIFICATION forming part of Letters Patent No. 691,650, dated January 21, 1902.

Application filed January 18, 1901. Serial No. 43,699. (No model.)

To all whom it may concern:

Be it known that I, NICHOLAS MONSHAUSEN, a citizen of the United States, and a resident of Milwaukee, county of Milwaukee, and State 5 of Wisconsin, have invented new and useful Improvements in Roofing-Tiles, of which the following is a specification.

My invention relates to improvements in that class of roofing which is shown and described in Letters Patent No. 516,570, which I now own and which were issued to me on the 13th day of March, 1894, by which construction the respective tiles comprising the roof are formed of earthenware, glass, or 15 other similar heavy material, which tiles are interlocked together and held in place by their own gravity.

By my present improvement the tiles are struck up or pressed out into the desired 20 shape from thin sheet metal, their inner and outer surfaces being one the direct converse of the other, by which peculiar shape each tile in a course laps upon its neighbor in such course and each successive course above the 25 first laps upon the one beneath it.

My improvements pertain more especially, first, to the peculiar construction of the 30 respective tiles, and, second, to the angular sheet-metal fastening-pieces located at the junction of the overlapping edges of the tiles in the respective courses.

My invention is further explained by reference to the accompanying drawings, in which—

Figure 1 represents a plan view showing several tiles in position as they are interlocked together in forming a roof. Fig. 2 is a transverse section drawn on line *x* *x* of Fig. 1. Fig. 3 is a longitudinal section drawn on line *y* *y* of Fig. 1. Fig. 4 represents a top view of the angular fastening-piece. Fig. 5 is a section drawn on line *t* *t* of Fig. 4, showing the tiles of the roofing in dotted lines. Fig. 6 is a section drawn on line *u* *u* of Fig. 1.

Like parts are identified by the same reference-letters throughout the several views.

A represents the main body of the tile, which is hexagonal in shape, and its general external configuration is substantially like 50 the external configuration shown in my said Patent No. 516,570. Extending longitudi-

nally through the center of each tile is a ridge B. From the ridge B the metal is curved downwardly in opposite directions toward the right and left to the flanges C and E. The 55 flanges E curve downwardly, so as to overlap and cover up the flanges formed at the upper ends of the tiles of the respective tiers. The respective side flanges C and the top flanges C' curve upwardly and then downwardly in the form of an inverted V, as shown upon the right and left in Fig. 2, by which arrangement said side flanges C are adapted to overlap and interlock with corresponding side flanges of the next adjacent 60 tiles in the course upon their respective sides, while the top flanges C and C' are adapted to be overlapped by and interlocked with the lower downward-projecting flanges of the adjacent tiles of the next succeeding tiers above. 70

To provide for the engagement of the concave surfaces of the V-shaped flanges C' C' with the convex surfaces I of the fastening-piece G, a rectangular notch L is formed at the lower ends of said flanges C' upon both 75 the right and left hand sides of each tile, so that the vertical edges of the notches of the two opposing tiles are brought together at a line drawn vertically through the center of said fastening-piece, whereby the head of the 80 nail J, which passes vertically through the fastening-piece, engages the respective edges K of said flanges without passing through the tiles. It will be obvious that when the tiles are thus secured in place the expansion and 85 contraction caused by heat and cold will have no tendency to draw out or loosen the nails or fastening-pieces or to tear or injure the tiles.

In laying the tiles the lower series are laid 90 first, beginning at the right, when the edges of each succeeding tile upon the left in the series overlaps its neighbor upon the right, as more clearly shown in Figs. 1 and 2. The first series being thus laid, the lower ends of 95 the next series, which are laid in like manner above it, overlap and cover the top flanges of the first series, whereby water flowing from each upper series is carried over the joints formed at the upper ends of the tiles of each 100 succeeding series below it.

As heretofore constructed the tiles of the

respective series were provided with downwardly-projecting angular lugs adapted to engage on horizontal cross-pieces secured to the roof, by which the tiles were retained in place 5 when interlocked together. By my improvement the downward-projecting lugs of the tiles and the horizontal cross-pieces of the roof heretofore used are dispensed with, the same not being adapted to be used with my 10 present form of sheet-metal tiles. By my present form of construction the angular locking-piece G is located at the upper end of the junction of each pair of tiles in each series of the roof. The fastening-piece G is 15 provided with a flat horizontal piece H, which rests upon the tile-supporting surface, and is provided with a V-shaped angular flange I, corresponding in shape with the under surface of the angular flanges C' of the tiles 20 which overlap and engage upon it. The fastening-pieces G having been inserted beneath the contiguous edges of the tiles, as shown in Fig. 1, they are secured in place by the nail J, the head of which is driven down 25 so as to engage upon the respective edges K K of the contiguous tiles. It will be obvious that the nail being thus inserted holds the locking-piece G in place upon the roof and prevents it from sliding upwardly or downwardly, while the head of the nail engages 30 the respective edges K of the tiles and prevents them from being raised out of contact with the locking-piece, and the concave surface of the locking-piece, which is nicely fitted 35 between the concave surfaces of the flanges C' of the tiles, prevents said tiles from sliding upward or downward, whereby such parts are all held rigidly in place. It will be understood that when the next succeeding series 40 or course of tiles are laid they entirely cover up and obscure from view the locking-

pieces G and the heads of the nails J as well as the joints formed by the contiguous edges of the tiles at K K. The several tiles of the roof being thus laid, it will be obvious that 45 they are all securely interlocked in such a manner that each successive course of tiles is held in place by the next succeeding course above it and all are rigidly and securely held in place. 50

Having thus described my invention, what I claim as new, and desire to secure by Letters Patent, is—

In a metallic roofing, the combination with a succession of courses of metallic hexagonal 55 roofing-tiles, having inversely-shaped interior and exterior surfaces, and provided with concavo-convex marginal edges, adapted to be overlapped and interlocked together; of angular sheet-metal fastening-pieces interposed 60 between the tiles and their support, said fastening-pieces being located at the upper end of the overlapping flanges of the two next adjacent tiles in the respective courses; and the concavo-convex surfaces of the angular 65 V-shaped elevations of said fastening-pieces being adapted to conform in shape to, and engage in, the concave surfaces of the angular top flanges of the two adjacent tiles above them; together with a fastening-nail inserted 70 centrally through said fastening-pieces, the head of which is adapted to engage the contiguous edges of the two adjacent tiles in the respective courses, all substantially as and for the purpose specified. 75

In testimony whereof I affix my signature in the presence of two witnesses.

NICHOLAS MONSHAUSEN.
